(57) **CLAIM**

The ornamental design for a smart active—smart active adjustment knob, as shown and described.

DESCRIPTION

FIG. 1 is a side perspective view of a smart active—smart active adjustment knob according to the present invention. FIG. 2 is a second side perspective view of the smart active—smart active adjustment knob of FIG. 1. FIG. 3 is a front view of the smart active—smart active adjustment knob of FIG. 1.

FIG. 4 is a front perspective view of the smart active—smart active adjustment knob of FIG. 1; and,

FIG. 5 is a third side perspective view of the smart active—smart active adjustment knob of FIG. 1.

The dashed lines illustrate environment that does not form a part of the present invention, and no claim is made to the material illustrated with dashed lines.

1 Claim, 5 Drawing Sheets
